(57) **CLAIM**

The ornamental design for a correction tape dispenser, as shown and described.

DESCRIPTIONFIG. 1 is an upper, front, and left side perspective view of correction tape dispenser showing the new design;
 FIG. 2 is a lower, front, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an upper, front, and left side perspective view thereof, showing the cover opened.
